UNITED STATES PATENT OFFICE.

JOHN McNEIL AND CHARLES McNEIL, OF GOVAN, SCOTLAND.

FIGURED ROLL FOR SUGAR-CANE MILLS.

No. 926,677.

Specification of Letters Patent.

Patented June 29, 1909.

Application filed November 30, 1908. Serial No. 465,191.

To all whom it may concern:

Be it known that we, JOHN McNEIL and CHARLES McNEIL, B. Sc., subjects of the King of Great Britain and Ireland, and residents of Govan, in the county of Lanark, Scotland, have invented certain new and useful Improvements in Figured Rolls for Sugar-Cane Mills, and of which the following is the specification.

10 Rolls for sugar-cane mills are provided with many forms of figuring consisting of a series of prismatic or bevel edged entablature like figures intercalated and arranged after many fashions, all to varying extent 15 suffer from the disability that they do not have sufficient purchase upon the cane to drag it through the rolls without slip. The present invention has for its object to overcome this disability.

20 According to the invention, the advancing edge, of any or all of such figures in which that edge is sufficiently near normal to the direction of motion and is sufficiently wide to cause slip in its normal state, instead of 25 being beveled as hitherto at an angle comparatively slight to the surface of the roll, is of such greater angle and so curved into the form of a cusp-like or claw-like tooth as effectively to seize the cane and draw it 30 through the rolls without slip.

An effective form of face is that in which the upper edge adjacent to the figure is radial or nearly radial to the roll and merges in a curve gradually increasing in quickness until 35 it joins the ground of the roll.

In order that the invention and the manner of performing the same may be properly understood there is hereunto appended a sheet of explanatory drawings showing diagrammatically in section in Figure 1 the advancing—or leading—and trailing edges of 40 the improved face, and in Fig. 2 an elevation of part of a roll with figuring of substantially known type but of the improved 45 form of face.

It will be seen in Fig. 1 that the upper and advancing edge A adjacent to the figure B is radial or nearly radial to the axis of the roll and merges in a curve C gradually increasing in quickness until it joins the ground D of 50 the roll, while the trailing edge—flank—of the figure merges in a sweeping curve E with the ground D.

In the example of figured roll shown in Fig. 2, the figuring of which elementarily 55 consists of a series of rectangular plateaux with their lengthy sides practically normal to the direction of motion of the roll, the up-standing and leading edges B of the figures are of the cusp- or claw-like form shown in 60 Fig. 1, while the “trailing” surfaces E merge gradually in the ground D of the roll.

It is obvious that the form of tooth described is applicable wherever the figures expose a sufficient length of face in a direction 65 normal to direction of motion of the roll to tend to cause slip.

What we claim is:—

1. In a sugar-cane mill roll, figuring exposing considerable lengths of face normal to 70 the direction of motion, and cusp-like or claw-like teeth formed upon the advancing edge of such figuring, as described.
2. In a sugar-cane mill roll, figuring exposing considerable lengths of face normal 75 to the direction of motion, cusp-like or claw-like teeth formed upon the advancing edge of such figuring and flanks merging into the ground of the roll, as described.

In testimony whereof we have signed our 80 names to this specification, in the presence of two subscribing witnesses.

JOHN McNEIL.
CHARLES McNEIL.
